Primary Examiner — Elizabeth J Oswecki(74) *Attorney, Agent, or Firm* — Vorys, Sater, Seymour & Pease LLP; William Klima(57) **CLAIM**

The ornamental design for a circuit board, as shown and described.

DESCRIPTION

The sole FIGURE is a front elevational view of a circuit board, showing our new design.

The broken lines shown in the drawings depict environmental structure or portions of the article that form no part of the claimed design.

1 Claim, 1 Drawing Sheet(56)
